UNITED STATES PATENT OFFICE.

JACOB KAUFMANN, OF ELKINS PARK, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

HEDDLE FRAME.

Application filed April 20, 1923. Serial No. 633,362.

To all whom it may concern:

Be it known that I, JACOB KAUFMANN, a citizen of the United States, residing at Elkins Park, in the county of Montgomery and State of Pennsylvania, have invented certain new and useful Improvements in Heddle Frames, of which the following is a specification.

My invention relates to heddle frames for 10 looms, and it relates more particularly to improved means for supporting the heddle bars intermediate their ends.

The principal object of my present invention is to provide improved means in a heddle frame for supporting the heddle bars intermediate their ends, which will securely support said bars against undesirable motion or displacement, but which, however, will permit the same to be readily and expeditiously mounted in and dismounted from 20 the frame when desired.

My present invention contemplates the provision of an improved form of device of the character aforesaid, which is simple, durable and efficient for its intended purpose, and which is particularly adaptable for that type of heddle frames in which there are provided pairs of heddle supporting bars at the top and bottom, respectively, as is often 30 the case when the warp ends controlled by the frame are closely arranged.

The nature and characteristic features of my invention will be more readily understood from the following description, taken 35 in connection with the accompanying drawings forming part hereof, in which:

Figure 1 is a front elevation of a heddle frame with supporting devices embodying the main features of my present invention 40 shown mounted therein;

Fig. 2 is a vertical transverse section thereof, enlarged, the section being taken approximately on the line 2-2 of Fig. 1;

Fig. 3 is a transverse sectional detail view, 45 still further enlarged, the section being taken approximately on the line 3-3 of Fig. 1;

Fig. 4 is a transverse sectional detail view, similar to Fig. 3, the section, however, being taken approximately on the line 4-4 of Fig. 1;

Fig. 5 is a view similar to Fig. 3, but with the parts in the positions assumed when it is desired to insert the heddle bars in the sup-

porting device, or to remove the same therefrom; and

Fig. 6 is a view, partly in elevation and partly in section, taken approximately on the line 6-6 of Fig. 3.

Referring to the drawings, the heddle frame there shown comprises top and bottom rails 8, usually made of wood and connected at their respective ends by means of the end straps 9 extending between said respective ends of the top and bottom rails 8. 65 Arranged near the top and bottom rails in the usual manner are the heddle bars 10, upon which the heddles 11 are mounted and supported. The heddle bars 10 may be arranged in pairs at the top and bottom, as 70 shown, this arrangement being preferably provided for close installations of the warp ends to obviate crowding of the heddles on the heddle supporting bars.

In the particular embodiment of my invention shown in the drawings, the device for supporting the heddle bars intermediate their ends, which comprises the novel portion of my present invention, may include a pair of angle brackets 12, each having a horizontal extension 13 and a vertical extension 14. The horizontal extensions 13 of the bracket members 12 are secured to the top and bottom rails 8 in any suitable manner. The vertical extensions 14 of the bracket 80 members 12 are preferably secured to each other by means of shouldered rivets 15, so as to provide a space 16 between the vertical extensions 14 of the bracket members 12. 85

The vertical extensions 14 of the bracket 90 members 12 are also each provided on each side with a recess 17, for the reception of the heddle supporting bars 10. The recesses 17 are of a width corresponding to the width of the heddle supporting bars 10, so that 95 when said heddle supporting bars are mounted in said recesses, the same will be supported against vertical movement or displacement of the intermediate portions thereof with respect to the frame.

Mounted in the space 16 between the vertical extensions 14 of the bracket member 12 is a slide member 18 having a central slot 19 through which the rivets 15 pass, the slot 19 being of such length as to limit the movement, in each direction, of the slide member 18, for a purpose to be presently explained. The slide member 18 is also provided on

each side with T-shaped recesses 20, the central portion of said recesses being of a width corresponding to the width of the recess 17 of the vertical extension 14 of the bracket member 12, and opening to the sides of the slide member as shown.

The bracket members 12 are also provided, adjacent the jointure between the horizontal extensions 13 and the vertical extensions 14, 10 with a slot 22, and on the outer surface of one of the vertical extensions 14 there is secured a leaf spring 23, which may be secured in place by one of the rivets 15, and having its free end 24 extending into the 15 slot 22 and bearing against the upper portion of the slide member 18. The free end of the leaf spring 23 may alternatively bear against the inner marginal edge of the slide member 18, or against the inner end of the 20 slot 19 in said slide member, accordingly as the slide member is in one or the other of the locking positions, as will be hereinafter described.

When it is desired to mount the heddle 25 supporting bars in the supporting device above described, the slide member 18 is brought to an intermediate position as shown in Fig. 5 of the drawings, so that the central open portion of the T-shaped recess 30 20 thereof will register with the recess 17 in the vertical extensions of the bracket members 12, and the outer end of the slide member 18 will register with the outer ends of the vertical extensions 14 of the bracket 35 members 12, as shown in Fig. 5 of the drawings. In this position the free end 24 of the leaf spring 23 will bear against the material of the slide member between the inner end of the slot 19 and the inner marginal edge 40 of said slide member, and by reason of the frictional engagement thereof will temporarily hold said slide member in said intermediate position as aforesaid. The heddle supporting bars 10 may now be inserted in or removed from the supporting device, as required, and when the same are inserted and it is desired to use the frame in the loom, the slide member will be shifted either up or down, whereby the off-set portions of each T-shaped recess 20 will engage the heddle supporting bar, and the overhanging lip 21, resulting from the T-shape of the recess 20, will serve to confine the heddle supporting bar within the recess 17 of 45 the vertical extension 14 of the bracket member 12. The leaf spring 24 will now engage either the inner marginal end of the slide member 18 or the inner end of the slot 19, accordingly as the slide member may be in the 50 raised or lowered position.

To facilitate the manipulation of the slide member, the portions of the vertical extensions 14 of the bracket member 12 beyond the recesses 17 are preferably made narrower 55 than the slide member 18, to thereby afford

a better finger hold on the slide member when it is desired to move the same from one position to another.

It will be noted, however, that in the event of the failure of the leaf spring 23 to properly function, the slide member 18 will fall by gravity to the locking position, and that, by reason of the T-shape of the recess 20 provided in said slide member, the same supporting device may be used both at the 75 top and bottom of the frame, and the slide member 18 will at all times function to lock the heddle supporting bars within the supporting device, and this regardless of whether the frame be reversed as to the top 80 and bottom thereof.

The supporting device, constructed as aforesaid, will be found to be exceedingly useful and efficient for its intended purpose, in that the same will at all times function 85 notwithstanding the continual stresses and knocks to which the heddle frames are subjected during the operation of the loom, and the likelihood of the heddle supporting bars becoming disconnected from the intermediate supporting device will be reduced to a minimum, as will be the destruction and disarrangement which usually results from fouling of parts of adjacent frames in the 90 loom.

Having thus described the nature and characteristic features of my invention, what I claim as new and desire to secure by Letters Patent is:

1. In a heddle frame, the means for supporting the heddle bars intermediate their ends comprising a bracket member secured to a portion of the frame, said bracket member having a vertically extending portion provided with a recess open toward the side and adapted to receive and support a heddle bar, and a slide member operatively associated with the vertically extending portion of said bracket member having a T-shaped recess the central portion of which is open toward the side and corresponds in width to the recess in the vertical extension of the bracket member, said T-shaped recess forming overhanging portions of said slide member above and below the central opening adapted to engage the heddle bar and thereby lock the same within the recess of the bracket member when said slide member is either in the upper or lower position.

2. In a heddle frame, the means for supporting the heddle bars intermediate their ends comprising a bracket member secured to a portion of the frame, said bracket member having a vertically extending portion provided with a recess open toward the side and adapted to receive and support a heddle bar, a slide member operatively associated with the vertically extending portion of said bracket member having a T-shaped recess the central portion of which

is open toward the side and corresponds in width to the recess in the vertical extension of the bracket member, said T-shaped recess forming overhanging portions of said slide member above and below the central opening adapted to engage the heddle bar and thereby lock the same within the recess of the bracket member when said slide member is either in the upper or lower position, and means adapted to positively limit the uppermost and lowermost positions of the slide member.

3. In a heddle frame, the means for supporting the heddle bars intermediate their ends comprising a bracket member secured to a portion of the frame, said bracket member having a vertically extending portion provided with a recess open toward the side and adapted to receive and support a heddle bar, a slide member operatively associated with the vertically extending portion of said bracket member having a T-shaped recess the central portion of which is open toward the side and corresponds in width to the recess in the vertical extension of the bracket member, said T-shaped recess forming overhanging portions of said slide member above and below the central opening adapted to engage the heddle bar and thereby lock the same within the recess of the bracket member when said slide member is either in the upper or lower position, and rivets secured to the vertically extending portions of the bracket member, and the slide member having a slot through which said rivets pass, said slot being of such length as to positively limit the uppermost and lowermost positions of the slide member.

4. In a heddle frame, the means for supporting the heddle bars intermediate their ends comprising a bracket member secured to a portion of the frame, said bracket member having a vertically extending portion provided with a recess open toward the side and adapted to receive and support the heddle bar, a slide member operatively associated with the vertically extending portion of said bracket member having a T-shaped recess the central portion of which is open toward the side and corresponds in width to the recess in the vertical extension of the bracket member, said T-shaped recess forming overhanging portions of said slide member above and below the central opening adapted to engage the heddle bar and thereby lock the same within the recess of the bracket member when said slide member is either in the upper or lower position, means adapted to positively limit the uppermost and lowermost positions of the slide member, and means adapted to maintain said slide member in the upper, lower or intermediate positions thereof as desired.

5. In a heddle frame, the means for supporting the heddle bars intermediate their ends comprising a bracket member secured to a portion of the frame, said bracket member having a vertically extending portion provided with a recess open toward the side and adapted to receive and support a heddle bar, a slide member operatively associated with the vertically extending portion of said bracket member having a T-shaped recess the central portion of which is open toward the side and corresponds in width to the recess in the vertical extension of the bracket member, said T-shaped recess forming overhanging portions of said slide member above and below the central opening adapted to engage the heddle bar and thereby lock the same within the recess of the bracket member when said slide member is either in the upper or lower position, means adapted to positively limit the uppermost and lowermost positions of the slide member, and a leaf spring adapted to maintain said slide member in the upper, lower or intermediate positions thereof as desired. 90

6. In a heddle frame, the means for supporting the heddle bars intermediate their ends comprising a bracket member secured to a portion of the frame, said bracket member having a vertically extending portion provided with a recess open toward the side and adapted to receive and support a heddle bar, a slide member operatively associated with the vertically extending portion of said bracket member having a T-shaped recess the central portion of which is open toward the side and corresponds in width to the recess in the vertical extension of the bracket member, said T-shaped recess forming overhanging portions of said slide member above and below the central opening adapted to engage the heddle bar and thereby lock the same within the recess of the bracket member when said slide member is either in the upper or lower position, rivets secured to the vertically extending portions of the bracket member, and the slide member having a slot through which said rivets pass, said slot being of such length as to positively limit the uppermost and lowermost positions of the slide member, and means adapted to maintain said slide member in the upper, lower or intermediate positions thereof as desired. 100

7. In a heddle frame, the means for supporting the heddle bars intermediate their ends comprising a bracket member secured to a portion of the frame, said bracket member having a vertically extending portion provided with a recess open toward the side and adapted to receive and support a heddle bar, a slide member operatively associated with the vertically extending portion of said bracket member having a T-shaped recess the central portion of which is open

- 1 toward the side and corresponds in width to the recess in the vertical extension of the bracket member, said T-shaped recess forming overhanging portions of said slide member above and below the central opening adapted to engage the heddle bar and thereby lock the same within the recess of the bracket member when said slide member is either in the upper or lower position,
- 10 rivets secured to the vertically extending portions of the bracket member, and the slide member having a slot through which said rivets pass, said slot being of such length as to positively limit the uppermost and lowermost positions of the slide member, and a leaf spring adapted to maintain said slide member in the upper, lower or intermediate positions thereof as desired.
8. In a heddle frame, the means for supporting the heddle bars intermediate their ends comprising a bracket member secured to a portion of the frame, said bracket member having a vertically extending portion provided with a pair of recesses open toward the sides and adapted to receive and support the heddle bars, and a slide member operatively associated with the vertically extending portion of said bracket member having a pair of T-shaped recesses the central portions of which are open toward the sides and correspond in width to the recesses in the vertical extension of the bracket member, said T-shaped recesses forming overhanging portions of said slide member above and below the central opening adapted to engage the heddle bars and thereby lock the same within the recesses of the bracket member when said slide member is either in the upper or lower position.
- 40 9. In a heddle frame, the means for supporting the heddle bars intermediate their ends comprising a bracket member secured to a portion of the frame, said bracket member having a vertically extending portion provided with a pair of recesses open toward the sides and adapted to receive and support the heddle bars, a slide member operatively associated with the vertically extending portion of said bracket member having a pair of T-shaped recesses the central portions of which are open toward the sides and correspond in width to the recesses in the vertical extension of the bracket member, said T-shaped recesses forming overhanging portions of said slide member above and below the central opening adapted to engage the heddle bars and thereby lock the same within the recesses of the bracket member when said slide member is either in the upper or lower position, and means adapted to positively limit the uppermost and lowermost positions of the slide member, and means adapted to maintain said slide member in the upper, lower or intermediate positions thereof as desired.
- 55 10. In a heddle frame, the means for supporting the heddle bars intermediate their ends comprising a bracket member secured to a portion of the frame, said bracket member having a vertically extending portion provided with a pair of recesses open toward the sides and adapted to receive and support the heddle bars, a slide member operatively associated with the vertically extending portion of said bracket member having a pair of T-shaped recesses the central portions of which are open toward the sides and correspond in width to the recesses in the vertical extension of the bracket member,

ends comprising a bracket member secured to a portion of the frame, said bracket member having a vertically extending portion provided with a pair of recesses open toward the sides and adapted to receive and support the heddle bars, a slide member operatively associated with the vertically extending portion of said bracket member having a pair of T-shaped recesses the central portions of which are open toward the sides and correspond in width to the recesses in the vertical extension of the bracket member, said T-shaped recesses forming overhanging portions of said slide members above and below the central opening adapted to engage the heddle bars and thereby lock the same within the recesses of the bracket member when said slide member is either in the upper or lower position, and rivets secured to the vertically extending portion of the bracket member, and the slide member having a slot through which said rivets pass, said slot being of such length as to positively limit the uppermost and lowermost positions of the slide member.

11. In a heddle frame, the means for supporting the heddle bars intermediate their ends comprising a bracket member secured to a portion of the frame, said bracket member having a vertically extending portion provided with a pair of recesses open toward the sides and adapted to receive and support the heddle bars, a slide member operatively associated with the vertically extending portion of said bracket member having a pair of T-shaped recesses the central portions of which are open toward the sides and correspond in width to the recesses in the vertical extension of the bracket member, said T-shaped recesses forming overhanging portions of said slide member above and below the central opening adapted to engage the heddle bars and thereby lock the same within the recesses of the bracket member when said slide member is either in the upper or lower position, means adapted to positively limit the uppermost and lowermost positions of the slide member, and means adapted to maintain said slide member in the upper, lower or intermediate positions thereof as desired.

12. In a heddle frame, the means for supporting the heddle bars intermediate their ends comprising a bracket member secured to a portion of the frame, said bracket member having a vertically extending portion provided with a pair of recesses open toward the sides and adapted to receive and support the heddle bars, a slide member operatively associated with the vertically extending portion of said bracket member having a pair of T-shaped recesses the central portions of which are open toward the sides and correspond in width to the recesses in the vertical extension of the bracket member,

said T-shaped recesses forming overhanging portions of said slide members above and below the central opening adapted to engage the heddle bars and thereby lock the same 5 within the recesses of the bracket member when said slide member is either in the upper or lower position, means adapted to positively limit the uppermost and lowermost positions of the slide member, and a 10 leaf spring adapted to maintain said slide member in the upper, lower or intermediate positions thereof as desired.

13. In a heddle frame, the means for supporting the heddle bars intermediate their ends comprising a bracket member secured to a portion of the frame, said bracket member having a vertically extending portion provided with a pair of recesses open toward the sides and adapted to receive and support the heddle bars, a slide member operatively associated with the vertically extending portion of said bracket member having a pair of T-shaped recesses the central portions of which are open toward the sides and correspond in width to the recesses in the vertical extension of the bracket member, said T-shaped recesses forming overhanging portions of said slide member above and below the central opening adapted to engage the heddle bars and thereby lock the same within the recesses of the bracket member when said slide member is either in the upper or lower position, rivets secured to the vertically extending portion of the bracket member, and the slide member having a slot through which said rivets pass, said slot being of such length as to positively limit the uppermost and lowermost positions of the slide member, and means adapted to maintain said slide member in the upper, lower or intermediate positions thereof as desired.

45 14. In a heddle frame, the means for supporting the heddle bars intermediate their ends comprising a bracket member secured to a portion of the frame, said bracket member having a vertically extending portion provided with a pair of recesses open toward the sides and adapted to receive and support the heddle bars, a slide member operatively associated with the vertically extending portion of said bracket member having a pair of T-shaped recesses the central portions of which are open toward the sides and correspond in width to the recesses in the vertical extension of the bracket member, said T-shaped recesses forming overhanging portions of said slide member above and below the central opening adapted to engage the heddle bars and thereby lock the same within the recesses of the bracket member when said slide member is either in the upper or lower position, rivets secured to the vertically extending portion of the bracket member, and

the slide member having a slot through which said rivets pass, said slot being of such length as to positively limit the uppermost and lowermost positions of the slide member, and a leaf spring adapted to maintain said slide member in the upper, lower or intermediate positions thereof as desired. 70

15. In a heddle frame, the means for supporting the heddle bars intermediate their ends comprising a pair of bracket members secured to a portion of the frame, said bracket members having vertically extending portions provided with recesses open toward the sides and adapted to receive and support the heddle bars, a slide member mounted between the vertically extending portions of said bracket members having T-shaped recesses the central portions of which are open toward the sides and correspond in width to the recesses in the vertical extensions of the bracket members, said T-shaped recesses forming overhanging portions of said slide member above and below the central opening adapted to engage the heddle supporting bars and thereby lock the same within the recesses of the bracket member when said slide member is either in the upper or lower position, and means adapted to positively limit the uppermost and lowermost positions of the slide member, and means adapted to maintain said slide member in the upper, lower or intermediate positions thereof as desired.

16. In a heddle frame, the means for supporting the heddle bars intermediate their ends comprising a pair of bracket members secured to a portion of the frame, said bracket members having vertically extending portions provided with recesses open toward the sides and adapted to receive and support the heddle bars, a slide member mounted between the vertically extending portions of said bracket members having T-shaped recesses the central portions of which are open toward the sides and correspond in width to the recesses in the vertical extensions of the bracket members, said T-shaped recesses forming overhanging portions of said slide member above and below the central opening adapted to engage the heddle bars and thereby lock the same within the recesses of the bracket member when said slide member is either in the upper or lower position, and means adapted to positively limit the uppermost and lowermost positions of the slide member, and a leaf spring adapted to maintain said slide member in the upper, lower or intermediate positions thereof as desired. 100 105 110 115 120

17. In a heddle frame, the means for supporting the heddle bars intermediate their ends comprising a pair of bracket members secured to a portion of the frame, said bracket members having vertically extending portions provided with recesses open 125 130

- toward the sides and adapted to receive and support the heddle bars, a slide member mounted between the vertically extending portions of said bracket members having T-shaped recesses the central portions of which are open toward the sides and correspond in width to the recesses in the vertical extensions of the bracket members, said T-shaped recesses forming overhanging portions of said slide member above and below the central opening adapted to engage the heddle bars and thereby lock the same within the recesses of the bracket member when said slide member is either in the upper or lower position, rivets extending between the vertically extending portions of the bracket members, and the slide member having a slot through which said rivets pass, said slot being of such length as to positively limit the uppermost and lowermost positions of the slide member, and means adapted to maintain said slide member in the upper, lower or intermediate positions thereof as desired.
18. In a heddle frame, the means for supporting the heddle bars intermediate their ends comprising a pair of bracket members secured to a portion of the frame, said bracket members having vertically extend-
- ing portions provided with recesses open toward the sides and adapted to receive and support the heddle bars, a slide member mounted between the vertically extending portions of said bracket members having T-shaped recesses the central portions of which are open toward the sides and correspond in width to the recesses in the vertical extensions of the bracket members, said T-shaped recesses forming overhanging portions of said slide member above and below the central opening adapted to engage the heddle supporting bars and thereby lock the same within the recesses of the bracket member when said slide member is either in the upper or lower position, rivets extending between the vertically extending portions of the bracket members, and the slide member having a slot through which said rivets pass, said slot being of such length as to positively limit the uppermost and lowermost positions of the slide member, and a leaf spring adapted to maintain said slide member in the upper, lower or intermediate positions thereof as desired.

In testimony whereof, I have hereunto signed my name

JACOB KAUFMANN.
